CAR ROOF

Filed Sept. 19, 1930

UNITED STATES PATENT OFFICE

CHARLES DAVID BONSALL, OF PITTSBURGH, PENNSYLVANIA, ASSIGNOR TO F. H. MURPHY COMPANY, OF NEW KENSINGTON, PENNSYLVANIA, A CORPORATION OF PENNSYLVANIA

CAR ROOF

Application filed September 19, 1930. Serial No. 482,949.

This invention relates to car roofs of the all-steel riveted-up type wherein the roofing sheets extend from side plate to side plate of the car and are provided with upstanding flanges along their sides, the flanges of adjacent sheets being rigidly clamped by a seam cover so as together to function as outside carlines. The principal object of the present invention is to devise a seam construction which will be more economical, more durable and more efficient in taking care of the stresses to which the roof is subject than present day roofs of the same type. The invention consists principally in making the seam cover with its side marginal portions thinner than the main portion thereof. It also consists in a seam construction wherein such a seam cover is riveted to the upstanding side flanges of the sheets with a space left below the rivets between such seam cover and said upstanding flanges; and it also consists in the parts and combinations of parts hereinafter described and claimed.

In the accompanying drawings wherein like reference numerals refer to like parts wherever they occur,

Fig. 1 is a plan view of a solid riveted up roof conforming to my invention,

Fig. 2 is a cross section through a seam thereof at the ridge,

Fig. 3 is a cross sectional view of the plate from which the cap of Fig. 2 is formed,

Figs. 4, 5 and 6 are the cross sectional views of modified designs of seam caps, and

Figs. 4a, 5a and 6a are respectively cross sectional views of the plate from which the caps of Figs. 4, 5 and 6 are formed.

The roof illustrated in Fig. 1 comprises sheets 1 that extend from side plate to side plate and have their ends riveted to such side plates 2. The sides of the sheets have raised panels 3 with upstanding flanges 4 along their outer edges. The adjacent upstanding flanges of adjacent sheets about 45 against each other and are covered by a seam cap or cover 5 consisting of a plate or heavy sheet rebent on itself longitudinally and provided with out-turned horizontal flanges 6 at its margins. Such seam cover or cap straddles the upstanding flanges 4 of the roof sheets

and is secured thereto by horizontally disposed rivets 7 that extend through both legs of the seam cap, whereby the seam cap and the sheet flanges are clamped firmly together and constitute, in effect, an outside carline construction.

According to the present invention, the seam cover is made of a plate of various thickness one or more longitudinal strips thereof being thicker than the adjacent strips. The design of plate illustrated in Fig. 3 is relatively thick throughout its body portion 8 and relatively thin throughout its side marginal portions 9, one of the faces having offsets that define the relatively thick middle or body portion from the relatively thin marginal portions. The thick body portion of this design is wide enough to extend below, but only slightly below the line of rivets. Preferably the cover plate is folded with its offset face inwardly as shown in Fig. 2, in which case the offsetting of the marginal portions leaves spaces 10 intervening between the upstanding flanges of the sheets and the respective legs of the seam cover. By reason of such spaces, capillary action is prevented and the sheets are afforded a certain leeway for movement in case of great stress thereon. However, the blank may be folded so that the offset face is outermost; in which case, the marginal portions may, if desired, be made thin enough to flex and let the sheets move. In either case, the more efficient distribution of metal makes it practicable to reduce the total weight of metal in the roof without sacrificing the strength thereof. Preferably the horizontal flanges 6 of the seam cover rest on the raised panel portions of the sheets.

By differentiating between the thickness of the body portion and the thickness of the marginal portions of the seam cover, the designer of the roof is afforded wide latitude in utilizing his structural materials to the best advantage in comparison with the restrictions occasioned by the use of sheets and plates of uniform thickness. For instance, it is obviously desirable that the sheets and seam cover shall be so designed as to cooperate in taking care of the roof load and other stresses, and various inventions have been made with

this end in view. According to the present invention, the metal in the seam cover can be massed where it is most efficient in taking care of stresses. For instance, in the construction 5 illustrated in Fig. 1, beam action is involved; that is, the roof sheets are adapted and arranged to take care of tensile stress and the portion of the seam cap above the neutral axis takes care of compressive stress, and the 10 designer, having control over the cross sectional shape and area of the seam cover, can adjust such cross section to the requirements of his computations. In this way, he can mass a considerable amount of metal at the 15 top of the seam cover, where it is most efficient in action and tends to raise the level of the neutral axis and thus to render the sheets more efficient in taking care of tensile stress.

Figs. 4, 5 and 6 represent various modifications 20 in the design of seam cap and Figs. 4a, 5a and 6a represent the respective plates from which they are made. The seam cap of Fig. 4 concentrates considerable metal at the 25 top thereof, the extra thickness being on the outside of the cap and resulting from folding the plate in the opposite direction to that of Fig. 2. The cap of Fig. 5 is formed by bending the plate at right angles along two 30 parallel lines at opposite sides of a thickened or offset strip on its outer face, said plate having on its inner face two additional thickened strips in position for the rivets to pass 35 through. This particular design has the merits of the first design plus special concentration of metal at the top thereof. The design of Fig. 6 is similar to that of Fig. 2 with 40 grooves formed above the rivets to economize metal. The several modifications shown in the drawings are intended to serve only as 45 illustrations of the latitude and freedom of design afforded by the present invention; as it is obvious that the invention may be embodied in other designs of seam cap and used with riveted seams whether the margins of the sheets are paneled or not.

What I claim is:

1. In a car roof, a seam construction comprising roof sheets with upstanding flanges and a seam cover straddling said flanges and secured thereto by horizontal rivets, the lower portions of said seam cap below the rivets being thinner than the upper portion thereof. 50
2. In a car roof, a seam construction comprising roof sheets with upstanding flanges and a seam cap straddling said flanges and secured thereto by horizontal rivets, the uppermost and rivet portions of said seam cap being thicker than the lower portion thereof. 55
3. In a car roof, a seam construction comprising roof sheets with upstanding flanges and a seam cover straddling said flanges and secured thereto by horizontal rivets, the upper portions of said seam cap being thicker than the lower portions thereof. 60
- 65 4. In a car roof, a seam cover comprising a

plate rebent along a line adjacent to its longitudinal middle line and having horizontal flanges along its sides, said seam cover having rivet holes through its vertical portions, and the side marginal portions of said seam cap being thinner than the body portions for widths extending almost to the rivet holes. 70

5. A seam cover for a car roof comprising a plate rebent along a longitudinal line and having horizontal flanges along its sides, said 75 seam cover having rivet holes through its vertical portions, and the uppermost part of said seam cap being thicker than the flange portions.

6. A seam cap for a car roof comprising a 80 rebent plate with horizontal flanges along its sides, said seam cap having rivet holes through its vertical portions, the top of such seam cap and the rivet portions thereof being thicker than the portions between them and 85 thicker than the side marginal portions of said seam cap.

7. In a car roof, a seam construction comprising roof sheets with upstanding flanges and a seam cap straddling said flanges and 90 secured thereto by horizontal rivets, the cross sectional shape of said cap being such that there is considerable concentration of metal at the uppermost part thereof.

Signed at New Kensington, Pennsylvania, 95 this 13th day of September, 1930.
